HENRY C. KNOWLTON, OF GARDNER, MASSACHUSETTS.

Letters Patent No. 83,713, dated November 3, 1868.

IMPROVED CHAIR-SEAT.

The Schedule referred to in these Letters Patent and making part of the same.

To all persons to whom these presents may come:

Be it known that I, HENRY C. KNOWLTON, of Gardner, of the county of Worcester, and State of Massachusetts, have invented a new and useful Improvement in Chair-Seats; and do hereby declare the same to be fully described in the following specification, and represented in the accompanying drawing, which denotes a transverse section of a chair-seat provided with my improvement.

The seats, on which my invention is based, are such as are usually composed of a wooden frame, and a bottoming of interlined rattan strips.

In the drawings, the said frame is shown at A, and the bottoming at B. This latter may be of the character as mentioned, or it may be of cloth, leather, or other suitable material.

The object of my improvement is to confine the bottoming to the frame, and at the same time, or afterwards, to effect the straining of the said bottoming. To this end I form the frame with its inner face or side arranged at an acute angle with the plane of the upper surface of the frame, such being as represented at a in the figure. The confining-bar C, by the aid of which the bottoming, near its edges, is to be clamped to the seat-frame, has each of its screw-holes b formed through it at an obtuse angle with that face of the bar which is to go next to the frame. Each of such holes should have a diameter somewhat greater than that of the shank of the screw D to go through, such hole and screw, when the latter is screwed into the frame, being arranged in manner as represented, so that when the screw is in the act of forcing the bar up to the frame,

it shall cause the bar at the same time to have an upward or sliding movement, such as will strain the bottoming, such, near its edge, being introduced between the bar and the frame.

Were the screw D arranged at right angles to the bearing-faces of the bar and frame, it would, while being set up, produce no upward movement of the bar. Therefore, it is the arrangement of the inner face of the frame at an acute angle with its upper face, in combination with the arrangement of each of the screws or its hole or holes at an obtuse angle with the bearing-faces of the bar and frame, that constitutes my improvement.

What, therefore, I claim as my invention in a chair-seat of the kind described, is—

The arrangement of the bearing-faces of the seat-frame and each of the confining-bars at an acute angle with the upper surface of the seat-frame, in combination with the arrangement of each of the clamping-screws, so as to incline upward at an obtuse angle with the said bearing-faces, the screw-hole in the confining-bar being made so as to admit of the upward movement of the bar while it may be in the act of being forced against the bottoming to confine it to the frame, the same serving to effect not only the fixation of the bottoming to the frame, but the straining or tightening of the said bottoming, and the setting of it up so as to be flush or even with or in its proper position with respect to the upper surface of the seat-frame.

HENRY C. KNOWLTON.
